SOAP DISPENSER

Howard L. Philippe, Chicago, Ill., assignor to The Imperial Brass Mfg. Co., Chicago, Ill., a corporation of Illinois

Filed Oct. 12, 1959, Ser. No. 57,901

Term of patent 14 years

(Cl. D4—3)

Fig. 1 is a front perspective view taken from the right side and top of a soap dispenser showing my new design;

Fig. 2 is a top plan view thereof;

Fig. 3 is a front elevational view thereof;

Fig. 4 is a left side elevational view thereof;

Fig. 5 is a rear elevational view thereof, the bottom of the container being broken away for convenience of illustration; and

Fig. 6 is a fragmentary bottom view of the front portion of the dispenser head.

The container portion of the soap dispenser depending from the dispenser head is translucent.

The characteristic features of my design for the soap dispenser disclosed reside in the dispenser head and bracket having the configuration shown.

I claim:

The ornamental design for a soap dispenser, as shown and described.
